RALF S. COCHRAN, OF TOLEDO, OHIO, ASSIGNOR TO SURFACE COMBUSTION CORPORATION, OF TOLEDO, OHIO, A CORPORATION OF NEW YORK

WALKING BEAM CONVEYER

Application filed September 6, 1930. Serial No. 480,068.

This invention relates to improvements in conveying apparatus adapted for moving work through a furnace in a series of steps or hops and has among its objects to provide a conveying apparatus of such form and construction that the longitudinal stroke thereof may be as long as desired without affecting the mechanism which controls the vertical stroke and which shall occupy but little space within the furnace and shall not require any special openings through the furnace roof, side walls or floor for the accommodation of the conveying mechanism. Other objects will more fully appear hereinafter.

Generally speaking, the conveyer comprises in combination with a laterally discontinuous bed on which the work rests while not being conveyed, a work-moving means comprising a longitudinally but not vertically reciprocating longitudinally extending support on which is supported a series of links which in turn support a longitudinally extending work-engaging member, means being provided for moving the longitudinally extending support independently of said member to raise and lower the latter with respect to said bed, and means being provided for moving said support and member in unison for moving said member longitudinally of said bed.

For a more complete understanding of the invention, reference is made to the detailed description taken in connection with the accompanying drawings forming part of this specification.

Referring to the drawings wherein the preferred form of the invention is shown:

Fig. 1 is a longitudinal side elevation of the conveying apparatus arranged within a heating furnace, the furnace being shown in vertical section and being more or less diagrammatically illustrated;

Fig. 2 is a transverse vertical section of line 2—2 of Fig. 1 and being on an enlarged scale as compared with Fig. 1;

Fig. 3 is a section on line 3—3 of Fig. 4 and illustrating the mechanism for causing relative movement between the work-moving member and the fixed work-supporting bed;

Fig. 4 is a transverse section on line 4—4 of Fig. 3;

Fig. 5 a fragmentary side elevation, parts being in section, illustrating certain details of the conveying mechanism and more particularly a modified form of link mounting;

Fig. 6 is a view similar to Fig. 5 but illustrating a still further form of link mounting, and

Fig. 7 is a diagram illustrating the cycle of movement of the work-moving member with respect to the work-supporting bed.

For the purpose of illustrating the application of the present invention, there is shown a tunnel-type furnace which intermediate its ends is provided with a depending bridge wall 10 of relatively great longitudinal length to form a restricted passage or throat T through which work from the preliminary heating chamber P must pass to enter the final or soaking chamber S. Rising from the opposite ends of the bridge wall 10 are walls 13 and 16 from the upper ends of which extend the walls 11 and 12 forming the arch or roof of the individual chambers P and S respectively. Positioned in the walls 13 and 16 are burners 14 and 17 respectively firing towards the ingress and egress ends 15 and 18 of the furnace, the end opening 18 being controlled by a door 19 and the opening 15 by a door 20, both being operated in any suitable manner by mechanism not shown. Firing into the ingress end of the furnace below the opening 15 therein are one or more burners 21. The floor 23 of the furnace may be lowered as at 23¹ to form an expansion chamber for the hot gases discharged by the burner 21. The furnace itself forms no part of the present invention.

Rising from the floor of the furnace are piers 25 and 26 which terminate at a common level and which are capped by metallic caps or saddles 27 having upstanding side flanges 27¹ defining a channel for laterally confining individual longitudinally extending rails 28, these rails being longitudinally but not vertically reciprocable with respect to the saddles 27 on which they are supported. The saddles and rails are formed of heat-resisting alloy. Anti-friction means are not necessary between the saddles and rails since sliding friction between highly heated heat-resisting

alloy parts produces a hard surface which is resistant to wear.

- 5 Mounted on the individual rails 28 are individual links 32 which in turn support a work-moving member or frame generally indicated at 29. The frame comprises a series of cross beams 31 on which are secured in laterally spaced relation, a series of longitudinally extending rails 30. According to 10 one form of link mounting there may be provided on the opposite ends of the cross beams 31 a longitudinally projecting member 35 beneath which the upper ends of the links 32 engage. The links 32 are of wedge shape at 15 their opposite ends to provide a knife-edge-type bearing. To prevent lateral displacement of the links with respect to the rails 28 and members 35, there may be provided upper and lower side lugs 33 and 34 respectively. 20 To prevent slippage of the links on the rails 28 the latter are provided with upstanding abutments 37 which may consist of parts welded to the rails.

25 As shown in Fig. 5 the upper end of the links 32 may engage beneath the rails 30 which the cross beams 31 support instead of engaging beneath an extension secured to the cross beam. In such event the under side of the rail would be provided with a depending abutment 37¹ to prevent slippage of the link. 30 As shown in Fig. 6 the upper end of the links may engage beneath the upper flange 31¹ of the cross beams 31 where the latter are of I-form in cross section as is preferred. To 35 provide proper clearance between the links and the cross beam the lower flange of the latter is provided with a cut-out as indicated at 31a.

40 From the foregoing description, it will be readily seen that relative longitudinal movement between the rails 28 and the frame or member 29, will cause the latter to be raised or lowered in parallelism with the rails 28. The links 32 are all of the same effective 45 length and the rails 28 and frame 29 are preferably confined to such relative longitudinal movement that the links will always extend obliquely with respect to the rails 28 in the direction of movement of work into the furnace. This is an important feature of the 50 invention since the frame 29 is thereby kept under longitudinal tension with the result that warping or twisting of the frame under heat is materially reduced or counteracted. 55 The frame 29 is movable through the plane of a laterally discontinuous bed generally indicated at 24 made up of a series of longitudinally extending rails 24¹ supported on cross beams 39 the ends of which are anchored in or 60 to the furnace side walls 40 in any approved manner. The rails 24¹ instead of being directly mounted on the cross beams 39 are mounted on stools 24a interposed between the rails and cross beams in order to provide the 65 proper clearance between the underside of

the bed 24 and the movable frame 29. As shown in Figs. 5 and 6 the various rails may if desired be provided with transverse apertures 38 to reduce the weight of the parts. It will be noted that the various rails and 70 cross beams are of commercially available form as to cross section and hence can be obtained at relatively low cost and require no machining to fit them for use. The links 32 are cast members and need not be machined. It will therefore be appreciated that 75 the conveying mechanism thus far described can be built at relatively low cost.

80 The means for actuating the rails 28 and frame 29 will next be described. 42 indicates parallel tracks extending longitudinally of the rails 28 in a plane therebelow. Mounted to run on the tracks 42 is a carriage generally indicated at 41. This carriage is of rectangular form made up of side beams 43 and end 85 cross beams 44. Extending transversely through the carriage are shafts 45 on the ends of which are mounted wheels 46 for running on the tracks 42. Secured to the inner sides 90 of the tracks are cylinders 47 for moving the carriage 41, the piston rod 48 of each cylinder being appropriately connected to the carriage as indicated at 49.

95 Mounted for reciprocation on the carriage 41 is a carriage generally indicated at 50, this carriage being of rectangular form comprising side beams 51 and end cross beams 52. Extending transversely through the carriage 50 are shafts 53 on the ends of which are mounted wheels 54 for running on tracks 100 formed by the side beams 43 of the carriage 41. Secured to the inner side beams 43 of the carriage 41 are cylinders 55 for moving the carriage 50 independently of the carriage 41, the piston rod 56 of each cylinder being appropriately connected to the carriage 41 as indicated at 57.

110 The outer ends of the rails 28 are mounted on and fixedly secured to the carriage 50 and hence longitudinal movement of the latter will cause corresponding movement of said rails. The frame 29 is flexibly secured to the carriage 41 in a manner to permit relative vertical but not longitudinal movement with respect thereto. To this end there is affixed to the carriage a pair of pedestals 58 each of which is connected to the frame 29 by longitudinally disposed links 59 secured to the frame in any appropriate manner as indicated at 60. To provide support for the overhanging portion of the frame 29 there may be provided links 61 coupled at their lower ends to the carriage 50 in any appropriate manner and at their upper ends to the frame 29. These links 61 are of the same effective length 115 as the previously described links 32. To provide support for the overhanging end of the bed 24 there may be provided a stand 62 supported at its lower end on the tracks 42 as 120 shown in Fig. 3.

From the foregoing description it will be readily appreciated that the carriage 50 may be moved independently of the carriage 41 and therefore that the rails 28 may be moved 5 longitudinally relatively to the frame 29 with consequent raising and lowering of the latter depending on the direction of movement of the carriage 50 and hence that the frame 29 may lift work from and redeposit it on the fixed bed 24 without relative longitudinal movement between the frame 29 and said bed. Also that longitudinal movement of the carriage 41 will cause longitudinal movement of the frame 29 in unison with the rails 28 when 10 the carriage 50 is stationary as the carriage 41. The cycle of movement of the frame 29 with respect to the bed 24 is illustrated in Fig. 7 from which it will be seen that such movement describes a rectangular path.

Any suitable means may be provided for 20 controlling the flow of motive fluid to the cylinders 47 and 55 in proper sequence to effect the above described movements and therefore have not been illustrated.

While the constructional features of the invention have been described with considerable detail, yet it will be apparent that considerable modifications in constructional features may be made without departing from 25 the spirit of the invention as defined in the appended claims and consequently I desire the construction to be taken as more or less indicative of broad features involved.

The present invention has special utility in 30 connection with furnaces for heating relatively long and flat work generally such as sheets, sheet bars and the like.

What is claimed is:

1. In apparatus for conveying work in a 40 series of steps or hops longitudinally of a work-supporting bed, the combination with such bed, of a longitudinally but not vertically reciprocable longitudinally-extending support beneath said bed, a work moving 45 member adapted to be moved both vertically and longitudinally with respect to said bed, a series of links supported on said support and in turn forming a support for said member, a longitudinally reciprocable carriage for 50 moving said member longitudinally, another carriage supported on said carriage for moving said support independently of said member, said member being flexibly connected to the first mentioned carriage in a manner to 55 permit vertical but not longitudinal movement with respect thereto, and said support being fixedly connected to the second-men- tioned carriage.

2. In apparatus for conveying work in a 60 series of steps or hops along a longitudinally extending bed within a furnace chamber, the combination of a carriage adjacent the outer end of said chamber, means for reciprocating said carriage toward and from said chamber, a second carriage mounted on the first

mentioned carriage, means for reciprocating the second carriage toward and from said chamber, a longitudinally extending member supported within said chamber and coupled at one end to the second carriage for reciprocation therewith, a second longitudinally extending member disposed within said chamber and secured at one end to the first-mentioned carriage, and rocker links between 70 said members for maintaining them in parallelism.

In testimony whereof I affix my signature.

RALF S. COCHRAN.
